(57) **CLAIM**

The ornamental design for a dental model base maker, as shown and described.

DESCRIPTION

FIG. 1 is a perspective view of a dental model base maker showing my new design;

FIG. 2 is a front elevational view thereof;

FIG. 3 is a rear elevational view thereof;

FIG. 4 is a right side elevational view with the left side being a mirror image thereof;

FIG. 5 is a top view thereof;

FIG. 6 is a bottom view thereof; and,

FIG. 7 is an environmental perspective view thereof.

The broken line showing of the dental model in FIG. 7 is for illustrative purposes only and forms no part of the claimed design.
